UNITED STATES PATENT OFFICE.

JOHN A. F. ASPINALL, OF LIVERPOOL, ENGLAND.

PROTECTED THIRD RAIL.

1,311,033.

Specification of Letters Patent.

Patented July 22, 1919.

Application filed July 24, 1914. Serial No. 852,885.

To all whom it may concern:

Be it known that I, JOHN AUDLEY FREDERICK ASPINALL, of Liverpool, in the county of Lancaster, in the Kingdom of England, engineer, have invented certain new and useful Improvements in Protected Third Rails, of which the following is a specification.

The present invention relates to an improved third rail for electric current collection particularly applicable to electric traction purposes such as electric railways, tramways and the like reference being made to the applicant's divisional application No. 256,255 filed September 30, 1918 showing and claiming the collector disclosed in this application.

According to the present invention current is collected from the side of one or more flanges of a flanged conductor rail in contradistinction to hitherto known methods of collection on the web, upper or under surfaces of the head of a conductor rail.

The rail is preferably of such a cross-section that its center of gravity lies so low that normal current collecting pressure upon the side of one of its flanges will not overturn it about its base even when its rail is not secured to the track.

30 The flange of the conductor rail which cooperates with the collector or contact shoe is preferably thickened to allow for wear of the rail.

The present invention will be more particularly described with reference to the preferred forms illustrated in the accompanying drawings, in which:

Figure 1 is a sectional elevation through part of the track and current collecting means.

Fig. 2 is a front elevation of the collecting shoe and supporting bracket.

Fig. 3 is an end sectional view of a modification.

45 Fig. 4 is a plan view partly in section of a modification.

Fig. 5 is a plan view of a ramp portion of the track.

Fig. 6 is an elevation of an insulator and cap.

Fig. 7 is a plan view.

Fig. 8 is a plan view of a modification.

Fig. 9 is an end view corresponding to Fig. 5.

55 Fig. 10 is a sectional end view of a modified form of rail.

The preferred form of rail is of channel section having a base flange 1 preferably broader than the head flange 2, but the flange head 2 is of greater depth or thickness than 60 the base flange 1.

By providing a broad base flange 1 it is secured that the center of gravity of the rail is lowered to the degree desired. The bearing surface 3 is preferably vertical as 65 in Figs. 1, 6, and 9, but it can be in certain cases inclined inward toward the web 4 from the head of the rail (see Fig. 3).

In one form of construction as shown in Fig. 3 a pair of substantially channel shaped 70 collector rails 5 and 6 are laid together with the inside edges of their flanges adjacent one another. In this preferred form it is then desirable to collect from the upper flanges 7 of the two rails and a single collector such 75 as 28, Fig. 4, can be arranged to bear on both these surfaces.

It will be seen that by the preferred disposition of the center of gravity of the rail these may be held in their supports without 80 the use of clips, screws, nails or other usual means, although such may be used if desired. It is preferred to secure the collector rails and their guards such as 8 and 9 by means of bent metal detachable clips 10. 85 These clips are preferably of channel section provided with special depressions for the reception of packing pieces of wood or the like, or locking keys such as 11. These locking keys 11 are preferably duplicate and interchangeable with the locking keys 12 of usual form serving to secure the vehicle supporting rails of the usual track 13 to the 90 usual chairs 14 where used.

The insulators supporting the collector 95 rails are preferably provided with a central portion 15 having a depression to receive a wooden block 46 for the reception of the rail, this portion being somewhat broader than the rail so that a space 16 is left between the rail and the guard 9 forming an outlet for water, snow, or like matter which would otherwise at certain times form an obstruction. The insulator is preferably provided with two side shoulders 17, 18, for 100 supporting the guards 9 and 8 respectively. The insulators have tapering bases 19 and can be secured to the sleepers 20 by angle clips 21 engaging said tapering sides 19. To simplify the track the sleepers 20 are 110 arranged to mutually support the insulators 19 and the chairs 14 for the permanent way.

13 or where chairs are not used for supporting the track, to support the rails directly.

The electric conductor rails are preferably connected together by the usual bending and 5 also by fish plates which are preferably arranged in a substantially horizontal plane connecting the lower flanges of the rail.

A packing or distance piece 22 (Fig. 1) is 10 preferably arranged between the web 4 of the conductor rails and the guard 9 arranged opposite the flanges of the conductor rails so that this guard 9 lies in spaced disposition relatively thereto providing a vertical slot 23 for the passage of the collector 15 shoe 28. The distance piece 22 can be loosely inserted between the rail and guard and pieces of similar formation may be used for fish plates or expansion joints secured by means of bolt and nuts 24 to rail flange 1. 20 The conductor rail is preferably provided with a recess portion 25 to receive one end of the bent metal distance piece or strip 22 to prevent it rising.

As shown in Fig. 3 a distance piece 22' 25 which may be of wood in the case of collection from two rails will be arranged between the rails 5 and 6.

The guards 8 for the collector rails are 30 preferably of L shaped cross-section and in certain cases it may be desirable to provide a curved or rabbeted portion corresponding to the curved portion of the rail with which it would engage, and it can be beveled at the top edge to allow greater clearance for the 35 current collector. The guard protecting the other side of the rail is preferably rectangular in cross-section as shown in Fig. 1.

In the case however of a double conductor rail shown in Fig. 3 the other guard will 40 similarly be of L-section. The guards are preferably of wood bearing directly on the rail. In certain cases, however, insulating packing pieces 26 could be interposed between guard and rail having a higher dielectric 45 strength.

The current collector or shoe 28 is preferably of rectangular form (Figs. 2 and 4). It may take the form of a pivoted plate 50 mounted on cylindrical trunnions 27 on a bracket 29 adjustable on a supporting plate 55 carried by the traction vehicle. The pivoted shoe 28 has pins 41 passing through bearings 42 on the brackets 29 so that by withdrawing the bolts 41 the shoe 28 will be readily detached from connection with the brackets 29 and other parts on the vehicle. The brackets 29 have a toothed inside surface 43 engaging with a corresponding surface on the plate 50 and are preferably provided with slots 44 which engage bolts 45 so that the plate 29 can be locked in any desired adjusted position. The upper end of 60 the pivoted plate 28 has a lug 30 to which the conductor leads 31 may be attached. A 65 cup 32 is mounted by means of a bolt 33 on

the upper end of the pivoted shoe 28 to receive a spring 34 which lies between this cup and an oppositely disposed cup 35 carried upon the vehicle. It will be seen that this spring 34 will tend to elastically press the 70 lower end of the collector shoe 28 into side contact with the portion 3 of the conductor rails.

Where the conductor rails terminate at 75 points or at a crossing, a ramp 36 is provided or the conductor rail may taper toward the outside of the track, in the case of a double line toward the space between the two running tracks to form a suitable guide 80 for the contact shoe 28 approaching toward the end of the conductor rail. In the case in which pressure of the contact shoe by means of the spring 34 is directed inward in a direction toward the corresponding running track, the guide or ramp 36 is made 85 inclined in the direction of the corresponding running track. This is considered preferable as it allows a greater clearance in the space between a pair of running tracks. The ramp portion 36 of the conductor rail can 90 if desired be isolated or made a dead length of rail by interposing a space between this rail and the next length of conductor rail 37, but the ramp and rail are preferably arranged continuous to make the rail more 95 stable at this point for the collecting shoe to strike against when moving on to the ramp previous to moving on to the conductor rail parallel with the track. The space where such is provided can be bridged over 100 by an insulating block 38 of wood or the like to form a continuous path for the contact shoe. A guard 39 is also provided for this ramp or guide rail. This is adapted to be supported near the end of the ramp by 105 brackets or caps 47 carried on the insulators of similar form to the normal third rail supporting insulators above described. The caps 47 also support the guards thus allowing one type of insulator to be used for the 110 conductor rail at all points; the guard is arranged to project some distance ahead of the rail or ramp which it protects as at 40, and also prevents any current arcing from the rail or collecting shoe to the ordinary running rails.

In order that a standard insulator may be used for supporting the end of the ramp-rail a detachable metal cap such as 47 is provided (Figs. 5 and 9) which has side 115 checks 48 against which the guards 9 and 39 may abut. This cap 47 slips over the top of the standard insulator used for supporting the third rails as above described.

To prevent any person accidentally entering 120 the end of the ramp rail between the outer end 40 of the main guard and the auxiliary guard 9 parallel to the track, an auxiliary guard piece 49 is arranged transverse 125 to the guards 39 and 9 across this open end 130

which may be held in place by the standard clip 10 and key 11.

In an alternative section to that described above the rail may be of girder section or 5 an inverted T-form with a thickened portion 81 on one side (see Fig. 10) at the base of the web which will then be uppermost to form a contact surface coöperating with the collector or contact shoe which will bear on 10 this side.

By the present system it will be seen that the advantage is obtained owing to a vertical motion of the collector relatively to the collector rail, the contact is not interrupted 15 until the end of the collector 28 has actually been lifted higher than the top contact surface of the rail 3. It will be seen that a 20 good contact will be obtained by this system in which the contact shoe bears on the side 25 of one of the rail flanges as the shoe will be held in contact with the collecting surfaces irrespective of slight irregularities of the track or other causes which would lift the collector shoe vertically relatively to the track.

The collector rail can be arranged either in the center of the track or upon the outside of the track, or again alternatively, in a double track the collector rails could be 30 arranged between the two lines of rails. The improved supporting system of the present invention has the advantage of a great saving in width so that particularly in the case in which the collector rails are arranged in 35 the space between two running tracks, greater space than heretofore is provided between these collector rails for plate layers or similar persons passing along the track in the performance of their duties.

40 In the simplest form of track of course the third rails will simply be laid upon the insulators. Such construction of track is illustrated in Fig. 6 and shows an end view of a rail on an insulator in position. The rail 60 rests on a wooden block 61 carried by a recessed portion of the insulator 62.

It is preferred to provide caps on the insulators such as 63. The cap is preferably 50 formed of a piece of stamped metal having upstanding tongues 64 thereon adapted to engage either side of the lower flange of the conductor or third rail. This cap may be 55 for instance the form shown in Fig. 7 held in place by lugs 65 on the insulator, or the form shown in Fig. 8 in which the cap is formed of one piece 66 fitting completely over the insulator and provided with downwardly turned lips 67. The upstanding lips 64 are preferably formed by punching out 60 of the metal strip so that there are spaces left in the center through which the wooden block 61 can project.

Instead of these caps it is possible to provide lugs on the wooden cushions for the 65 rails such as 68, Fig. 9.

Stops may be provided on the vehicle or brackets thereon to prevent undue movement of the collecting shoe so that it will be in convenient position to enter the ramp after it has left a rail at points or the like. 70

The guards 8 and 9 are preferably provided with extension portions 70 (Fig. 1) reaching below the bottom of the conductor rail.

It is preferred to provide a guard for the 75 collector shoe and this may consist of a casting consisting of two end boards 75 (Fig. 1) to which is hinged at 76 a flap 77 which flap is locked in position by any desired securing means such, for instance, as a wing bolt and 80 nut connection 78 engaging in slots 79 in the cover 77.

If desired the rail may be rolled with ribs 80 on its under surface engaging the sides of the wooden block recessed in the insulator 85 (Fig. 10).

I declare that what I claim is:—

1. In a third rail system, a third rail having a vertically disposed working side face, an insulator adapted to be secured to a 90 sleeper, and having shoulders at its opposite sides, a cushion between the shoulders upon which the rail loosely rests, an inner angle guard resting at its lower edge on one of said shoulders with its upper horizontal 95 member overlying the top surface of the rail, a second or outer guard resting at its lower edge on the other shoulder and from which the base of the rail is spaced to permit exit of water, etc., a clamp having ends 100 one of which engages the outer side of the outer guard and the other of which extends up parallel with the inner guard, and a locking key between the inner guard and the adjacent end of said clamp. 105

2. In a third rail system, a third rail having a vertically disposed working side face and a web parallel thereto, an insulator having a cushion on its upper face upon which said rail loosely rests; said insulator having 110 shoulders at opposite sides of the rail, an angle guard resting at the lower edge of its vertical member upon the inner shoulder and extending at its upper horizontal member across the upper surface of the rail, a 115 second outer guard resting at its lower edge upon the outer shoulder, a drain space being formed between the rail and the outer guard, a spacing member between the web of the rail and outer guard, and clamping means 120 holding the two guards to the rail and insulator.

3. In a third rail system, a third rail having a vertical working side face, an insulator adapted to be secured to a sleeper, a cap 125 on said insulation supporting the third rail, shoulders on said cap, and guards held in spaced relationship by said shoulders.

4. In a third rail system a third rail having a vertical working side face, an insula- 130

tion adapted to be secured to a sleeper, a cap fitting on said insulator and having a socket, a cushion in said socket supporting the third rail, shoulders on said cap, and guards held in spaced relationship by said shoulders.

5. In a third rail system, a third rail having a vertical working side face, an insulator adapted to be secured to a sleeper, a cap on said insulator supporting the third rail shoulders on said cap, an inner angle guard resting at its lower edge on one of said shoulders with its upper horizontal member overlying the top surface of the rail, and a second or outer guard resting at its lower 10 edge on the other shoulder.

15

6. In a third rail system, a third rail having a vertical working side face, an insulator adapted to be secured to a sleeper, a cap on said insulator supporting the third rail, shoulders on said cap, guards, and a bent 20 metal spring clamp embracing the guards and rail to hold the said guards against the shoulders.

In witness whereof, I have hereunto signed my name this 11th day of July 1914, in the 25 presence of two subscribing witnesses.

JOHN A. F. ASPINALL.
